(57) **CLAIM**

The ornamental design for a soundhole for a semi-acoustic electric guitar, as shown and described.

DESCRIPTION

FIG. 1 is top-front-left perspective view of a soundhole for a semi-acoustic electric guitar in accordance with the present design;

FIG. 2 is an enlarged view thereof;

FIG. 3 is a left-side view of FIG. 1;

FIG. 4 is a right-side view thereof;

FIG. 5 is a top view thereof;

FIG. 6 is a bottom view thereof;

FIG. 7 is a front view thereof; and,

FIG. 8 is a rear view thereof.

The broken lines represent environmental structures of a semi-acoustic electric guitar that form no part of the claimed design.
